Nelson W. Hobson

UNITED STATES PATENT OFFICE.

GEORGE H. BLACK, OF ROCHESTER, NEW YORK, ASSIGNOR TO UNITED SHOE MACHINERY CORPORATION, OF PATERSON, NEW JERSEY, A CORPORATION OF NEW JERSEY.

MANUFACTURE OF WELT-SHOES.

1,353,308.

Specification of Letters Patent. Patented Sept. 21, 1920.

Application filed December 28, 1918. Serial No. 268,638.

To all whom it may concern:

Be it known that I, GEORGE H. BLACK, a citizen of the United States, residing at Rochester, in the county of Monroe and 5 State of New York, have invented certain Improvements in the Manufacture of Welt-Shoes, of which the following description, in connection with the accompanying drawings, is a specification, like reference characters on the drawings indicating like parts 10 in the several figures.

The present invention relates to the manufacture of boots and shoes and more especially it concerns the manufacture of shoes 15 of the well-known Goodyear welt type.

In the manufacture of welt shoes the welt tends to pucker or plait in conforming to the curvature at the toe of the shoe, this being particularly true in pointed shoes 20 which are usually made with a thin welt and a thin sole in order to simulate in appearance the light, close edge obtainable in a "turn" shoe. As the result of this thickening or puckering of the welt around the toe 25 of the shoe it is impossible to trim the inseam as "close" at this point as along the sides of the shoe, which acts to warp or distort the outsole when it is applied. Thus the thickness of the sole edge around the toe is 30 increased relatively to the thickness of the sole edge along the sides of the shoe and a heavy and clumsy appearance is produced at the toe of the shoe where the reversed condition is most desired.

35 The principal object of the present invention is to provide an improved process of making welt shoes the practice of which will eliminate the above-mentioned and other disadvantages heretofore encountered and 40 will result in superior shoemaking and a more attractive appearing shoe.

In one of its aspects the invention consists in reducing the thickness of the toe portion of the outsole to compensate for the 45 puckering of the welt of the shoe where it is conformed around the toe portion. As herein illustrated, this reduction in the thickness of the toe portion of the outsole is obtained by removing a thin skiving of material from the flesh side of the toe portion 50 of the outsole so that when the toe portion of the outsole is seated upon the shoe bottom at the toe the thickness of the skived

edge of the sole, together with the thickness of the welt, will be substantially equal 55 to the thickness of the sole plus the welt along the sides of the shoe.

The invention will now be more fully explained in connection with the accompanying drawing which illustrates a preferred 60 practice of the invention and the novel features will then be pointed out in the claims.

Figure 1 is a perspective view, partly in section, of a welted shoe which has been made in accordance with the preferred practice of the present invention; 65

Fig. 2 is a view illustrating the treatment of the outsole in accordance with this invention to adapt it for application to the 70 shoe;

Fig. 3 is a perspective view of the toe portion of the completed shoe.

Fig. 4 is a perspective view illustrating the condition produced by the welt in conforming to the curvature at the toe of the 75 shoe.

Fig. 5 is a view illustrating the action of an edge setting iron upon the edge of a sole.

In the practice of the invention a shoe is lasted, welted and otherwise prepared for 80 soling in the usual or any suitable way. In the welt attaching operation the welt 2 unavoidably fulls and thickens where the welt strip is bent edgewise in forming it to the

shoe toe, the extent of the thickening increasing as the bend becomes sharper on pointed toes. It is customary to trim the 85 between-substance 4 as close as practical to the inseam stitches 5 at all points and to beat the welt to make it lay as snugly as

possible to the feather 6 of the insole but in spite of the best that can be done the thickness of bottom stock at the end of a narrow toe is greater than at adjacent parts of the 90 shoe, and this is very noticeable in a pointed-toe woman's shoe which is designed in an effort to present an appearance of lightness.

The defect is conspicuous when, as is frequently desirable, the edge is trimmed and 95 "set" or burnished to present a main portion or "bed" 3, Fig. 5, and a narrow bevel

7 at the upper or the lower corner or both of the bed. The width of the bed face on the finished edge is predetermined by the 100 edge setting tool and any excess of width of 105 stock shows up prominently as an exaggerated

ated or uneven width of the normally narrow bevel.

In accordance with this invention, this objectionable thickness is offset or counterbalanced by reducing that marginal portion of the sole at the toe which is to underlie the objectionably thick portion of the welt. In practising the invention satisfactory results have been obtained by removing a suitable skiving from the flesh side of the toe portion of a sole blank or block sole 8, as at 10. The reduction in thickness is made to extend far enough back from the edge of the toe to include the portion which lies under 15 the welt and the inseam, but not far enough back to weaken the wearing quality of the sole. The sole is then laid with the reduced portion in proper relation to the welt and is stitched to the welt in the usual manner.

20 After the edge of the sole and welt has been shaped and the surplus projection of the welt and upper has been cut away in the usual edge trimming operation, the edge is set by the usual edge setting iron, appropriate pressure being applied to produce the bed of the finished edge and the bevel 7 at the top and (or) bottom corner of the bed. For proper appearance the bevel or bevels must be of substantially uniform width and must 25 not be conspicuously wider around the end of the toe than at the sides. This result is insured by reducing the outsole at the toe at least enough to compensate for the fulling of the welt at the toe. If the reduction is 30 slightly more than necessary, no harm is done because the edge can be thickened by appropriate pressure against the edge setting iron sufficiently to provide the stock for forming the desired bevel, this being ex- 35 pected of the operative who performs the 40 edge setting.

Having explained the nature of the invention and described how it may be practised,

I claim as new and desire to secure by Letters Patent of the United States:—

1. That improvement in the art of making welt shoes which consists in bending a welt strip edgewise around the toe of the shoe in the operation of attaching the welt and trimming the inseam to prepare the shoe 50 for the reception of the outsole; preparing the outsole to present with the welt a substantially uniform thickness of edge around the forepart of the shoe by removing from the flesh side of the toe portion of the outsole sufficient stock to compensate for the thickening of the welt which occurred in bending it around the toe; and applying the sole with the reduced portion thereof in proper relation to the thickened portion of 55 the welt to produce an edge which is of substantially the same thickness at the toe that it is at the sides of the shoe.

2. That improvement in the art of making welt shoes which consists in compensating 60 for excessive thickness of welt at the end of pointed-toe shoes by reducing the outsole to present with the welt substantially the same thickness of bottom stock from the inseam outwardly at the end of a pointed toe as at 65 the sides of the toe.

3. That improvement in methods of obtaining uniformity in edge face appearance around the forepart of a welt shoe sole which consists in reducing the marginal portion of 70 the sole at the toe at least enough to compensate for an increase in thickness of the welt where it is bent around the toe and, after the sole is trimmed, setting the edge with appropriate pressure to produce there- 75 on a bed and a uniform width of bevel or bevels at the corner or corners of the bed at the sides and toe end of the forepart.

In testimony whereof I have signed my name to this specification.

GEORGE H. BLACK.
